FLUID OPERATED DIVING PLATFORM

Jay G. Stephenson, Chattanooga, Tenn.

Application April 25, 1939, Serial No. 270,039

9 Claims. (Cl. 272—57)

This invention relates broadly to improvements in fluid operated vertically movable platforms or supports and pertains particularly to a novel diving platform for swimmers.

The present invention has for its primary object to provide a play device for use in swimming pools by means of which a diver, after climbing onto the platform, will be raised through the operation of automatically operating mechanism, to a predetermined height from which a dive may be made, after which the platform will be automatically returned to its lowered position so that another diver may make use of the same.

A further and more specific object of the invention is to provide a fluid operated diving platform arranged or mounted for vertical movement and having associated therewith a novel mechanism whereby when a weight is applied thereto fluid pressure will be brought into operation to raise the platform to a predetermined height and when such predetermined height is reached, such fluid pressure will be shut off and escape means opened so that the pressure of the fluid will be released to permit the platform to return to its normal lowered position.

Another object of the invention is to provide in a structure of the above described character, a novel dual valve control mechanism by means of which a pair of valves constituting inlet and exhaust means for the compressed operating fluid for the platform, may be simultaneously actuated so that when the inlet valve is opened, the exhaust valve will be shut and vice versa.

The invention will be best understood from a consideration of the following detailed description taken in connection with the accompanying drawing forming part of this specification, with the understanding, however, that the invention is not to be confined to any strict conformity with the showing of the drawing but may be changed or modified so long as such changes or modifications mark no material departure from the salient features of the invention as expressed in the appended claims.

43 In the drawing:

Fig. 1 is a view in longitudinal section of the platform structure embodying the present invention.

Fig. 2 is a view in elevation of the lower part of the structure showing the valve control mechanism in the position where the operating fluid is cut off from entering the pressure cylinder and the fluid within the cylinder may be permitted to escape.

Fig. 3 is a view similar to Fig. 2 but showing

the control valves in the reversed position from Fig. 2.

Fig. 4 is a sectional view taken substantially on the line 4—4 of Fig. 2.

Referring now more particularly to the drawing, the numeral 1 generally designates a piston cylinder, the lower end of which may be closed in any suitable manner but is here shown as having a base plate 2 coupled therewith by means of the upstanding collar 3 and provided with openings 4 through which suitable securing bolts or other devices may be passed for maintaining the cylinder in vertical position within a swimming pool or in any other position where the platform is to be used.

In the lower part of the cylinder 1 there is extended through the wall of the cylinder the combined fluid inlet and exhaust pipe 5 which at its outer end is joined with a pipe 6 which has thereon upon opposite sides of the pipe 5, the fluid inlet and exhaust valves 7 and 8, respectively. Each of these valves includes a rotary plug 9 having a transversely extending head piece 10, the position of which indicates whether the valve is opened or closed, the head piece extending longitudinally of the pipe 6 when the valve is open and transversely thereof when the valve is closed. Thus it will be seen that in Fig. 2 the valve 7 which controls the flow of fluid toward the pipe 5 and into the cylinder, is shut and the valve 8 is open so that the exhaust valve is open so that fluid may escape from the cylinder 1.

The heads 9 of the inlet and exhaust valves carry actuating arms 11, each of which has at its outer end a laterally extending pin 12. These arms are arranged to be always in parallel relation and they are coupled together to maintain this relation, by a coupling rod 13, the ends of which are pivotally attached to the arms 11 of the valves so that these arms may rock between the opened and closed positions for the valves while the rod 13 merely moves along a straight path or rectilinearly.

Extending transversely of the cylinder above the pipe 6 and perpendicularly thereto, is a rock shaft 14, one end of which may be suitably housed in a bearing socket 15 formed in the wall of the cylinder 1, as shown in Fig. 4, while the other end passes through the packed bearing 16 to the exterior of the cylinder as is also shown in this figure. Upon the extended or outer end of the rock shaft 14 is secured a collar 17 which carries the oppositely directed crank arms 18 and 19. The arm 18 extends downwardly and in substantially the same direction as the valve arms 55

11 and to its lower end is pivotally attached by the pin 20, the ends of a pair of links, each of which is indicated by the numeral 21. Each of these links has a longitudinally extending slot 22 adjacent its outer end and in this slot is slidably engaged a pin 12 of a valve arm 11.

Upon the outer side of the cylinder 1 above the rock shaft 14 there is pivotally mounted a rocking bracket 23 which forms a part of a snap-over mechanism which is coupled with the upper crank arm 19 through the medium of a pin 24, the upper end of which has slideable connection with the bracket 23 while the lower end is pivotally coupled with the arm 19, as indicated at 25, and an expansion spring 26 which is interposed between the pivoted portion 25 of the pin 24 and the oscillating bracket 23. This expansion spring normally maintains the rock shaft 14 in one of two positions and is under compression when the rock shaft is turned to a position where the cranks 18 and 19 are vertical so that as soon as these cranks pass the vertical position, the spring can take control to snap the cranks and the rock shaft over to one or the other of the two positions in which it is shown in Figs. 2 and 3.

The links 21 and the slots 22 are so proportioned that when the rock shaft arms 18-19 are in either of the two oblique positions with respect to the cylinder 1, one valve arm pin 12 will be in the end of a slot 22 while the other one will be removed from the outer end of its slot, as shown. The distance between this latter pin and the outer end of the slot from which it is spaced is such that when the shaft 14 is rocked 30 in the direction necessary to move the link connected with the latter pin so as to shift this pin into the end of its slot, the link will have free movement on the pin until the rock shaft 14 is 35 in its half-way position, or in other words, until the cranks 18 and 19 are vertical and the spring 40 26 is fully compressed. Then the said latter pin 12 will be disposed in the outer end of its slot and when the snap-over mechanism operates to oscillate the rock shaft, this latter pin will be 45 pulled by the adjacent link to oscillate the adjacent valve.

Within the cylinder 1 there is mounted upon the rock shaft 14 a thrust arm 21, the outer end of which is connected with a thrust link 23. The actuation of these members will be herein-after more fully described.

Within the upper end of the cylinder 1 is an elongated collar or bushing 47 and this bushing is secured in place by welding, rivets or the like. The top end of the cylinder may be finished off with a cap such as is indicated at 29, and between this cap or the top end of the cylinder, if such cap is not used, is an expansion spring 32 which surrounds the sleeve. The numeral 33 designates the platform for the present structure and to the underside of this platform is fixed a threaded collar 34 to which is attached the upper end of a tubular rod 35. This rod passes through the cap 31 and longitudinally through the sleeve 30 to the inner end of the latter and terminates in a head 36 which has upon its underside the threaded recess 37 which is coaxial with the tube. Opposing the head 36 of the tubular rod is a nut 38 which has a reduced threaded portion 39 which extends into the recesses 37 of the head and this nut clamps against the lower end of the sleeve and the head 36, a cup washer 40 and an annular plate 41. The cup washer constitutes a piston which slides within the piston cylinder 1.

The nut 38 has a central passage 42 therethrough and extending through this passage is a coupling rod 43, the upper end of which passes into the tubular rod 35 and carries a head 44 which is of sufficient size to prevent the upper end of the rod being drawn through the passage 42 of the nut 38. The lower end of this coupling rod 43 extends into the piston cylinder 1 and has a foot piece 45 secured thereto to which is pivotally attached the thrust link 28. The connection between the thrust link and the foot piece 45 is off center with respect to the longitudinal center of the coupling rod. 5 10

Surrounding the coupling rod 43 and fixed thereto is a stop plate 46 for the piston 40. This plate is apertured as shown, so that fluid employed for moving the piston, whether the same be air or water, may pass through and exert pressure against the underside of the piston. When the spring 32 is fully expanded, as shown in Fig. 1, there will be a space between the piston 40 and the stop plate 46 and when the parts are in the position shown so that the thrust arm 21 is extending upwardly within the piston cylinder, the valve snap-over mechanism will be in the position in which it is shown in Fig. 2, that is, with the inlet valve 7 closed and the outlet valve 8 opened.

The operation of the present mechanism is as follows: When the parts are in the position shown in Fig. 1, it will be assumed that if the device is placed within a swimming pool, the platform 33 will be near the surface of the water so that a diver may easily get thereon. As previously stated, the fluid inlet control valve 7 will be closed and the outlet valve 8 will be opened. If a weight is now placed upon the platform 33, as for example, a diver getting onto the platform, the sleeve 30 will be forced down against the resistance of the spring 32 and will move the piston 40 against the stop plate 46. As the stop plate is secured to the coupling rod 43, this will force the coupling rod down and will actuate the arm and link mechanism 27-28 to rock the shaft 14 against the resistance of the snap-over spring 26. As the shaft arms 18-19 swing past vertical or center position where the spring 26 will be fully compressed as previously explained, the link 21 which is coupled with the arm 11 of the outlet valve 8, will engage the adjacent pin 12 in the outer end of its slot and as the spring 26 expands so as to snap the arms 18 and 19 to the opposite oblique position with respect to the cylinder, the outlet valve plug will be oscillated so as to shut this valve. At the same time, motion will be transmitted through the rod 13 to the arm 11 of the inlet valve 7, to swing the plug of this valve to opened position. This will allow fluid to flow into the cylinder 1 through the pipe 5 and cause the piston and platform 33 to be raised.

The length of the coupling rod 43 is so proportioned that as the piston nears the top of its stroke under the influence of the inflowing fluid, the coupling rod head 44 will be engaged by the upper side of the nut 38 and an upward pull will then be transmitted to the coupling rod 43 so as to reversely rock the shaft 14 through the medium of the parts 27 and 28 to actuate the snap-over mechanism for the valves so as to reverse the operation above described in connection with the actuation of the valve arms by the links to return the valves to the position where the inlet valve will be closed and the outlet valve will be opened. This will permit the fluid within 70 75

the cylinder beneath the piston 49 to escape and the piston and platform to return to its normal lowered position where it will be held by the spring 32 in the manner illustrated in Fig. 1.

5 It will be understood, of course, that the diver being raised by the platform 33 may dive therefrom at any time before the platform reaches the upper limit of its movement and if the diver leaves the platform before the upper limit is reached, the platform will continue to rise until the mechanism is actuated as described, so as to shut off the fluid pressure and release the fluid from the cylinder. After the platform has returned to its lowered position, the parts will be 10 set so that when another swimmer gets onto the platform, the above operation will be repeated for the raising and lowering of the platform.

By the provision of the cylinder reducing collar or bushing 47, means is provided which will prevent the piston being forced out of the cylinder in the event that the valve operating mechanism should, for any reason, fail to operate. This collar also serves to provide a relatively long extent of support for the sleeve when the piston reaches 23 the top of its movement so as to prevent any tipping or swaying of the platform and sleeve as might result if the piston were permitted to go entirely to the end of the cylinder and the sleeve did not have such an enclosing guide.

303 What is claimed is:

1. In a structure of the character described, a platform, means supporting the platform for vertical movement, fluid pressure actuated mechanism for imparting upward movement to said means, means for shutting off the application of fluid pressure when said first means reaches a predetermined elevated position and for simultaneously relieving the fluid pressure by which the platform was raised, and means by which said 40 fluid pressure may again be applied for the raising of the platform supporting means by the application of downward pressure to the platform when the latter has been restored to its normal lowered position.

45 2. A device of the character described, comprising a vertically movable body, a fluid actuated piston connected with said body, a platform supported by the body, a cylinder for the piston, means for conducting fluid into the cylinder beneath the piston, an inlet control valve for said means, means for exhausting fluid pressure from the cylinder, mechanism connected with said valve and said last means which when actuated will effect the simultaneous opening of the valve 55 and closing of the exhaust means or opening of the exhaust means and closing of said valve, means operating upon the application of a weight to the platform for the actuation of said mechanism to open said valve and close said exhaust means, and means operating upon the movement of said piston upwardly to a predetermined position for actuating said mechanism to close said valve and open said exhaust means.

60 3. A device of the character described, comprising a fluid actuated platform supported for vertical movement, valve controlled means for effecting the upward movement of the platform by fluid pressure, valve controlled means for exhausting the fluid pressure for the lowering of the 70 platform, means resiliently supporting the platform in a lowered position, means operating upon the compression of the resilient supporting means by the application of a weight to the platform to effect the operation of the first-mentioned valve 75 control means to apply fluid pressure for the

raising of the platform and to simultaneously actuate the second-mentioned valve controlled means for the shutting off of the exhausting of the fluid pressure, and means operating upon the movement of the platform to a predetermined raised position to open the valve controlled fluid exhaust means and to close the valve controlled fluid pressure applying means.

4. A structure of the character described, comprising a vertically disposed cylinder, a piston 10 within the cylinder, a platform disposed above the cylinder and connected with said piston, resilient means normally maintaining the platform in spaced relation with the cylinder when the platform is in lowered position, a valve controlled fluid inlet for the cylinder beneath the piston, a valve controlled fluid outlet for the cylinder beneath the piston, means coupling the valves of the fluid inlet and outlet for simultaneous movement, one of said valves being 20 opened while the other one is closed, means actuated by the piston upon the downward movement of the platform against said resilient supporting means to effect the actuation of the valve connecting means whereby the fluid inlet valve will be opened and the fluid outlet valve will be closed, and means engaged and actuated by the piston upon its upward movement to a predetermined position for reversely actuating the valve connecting means whereby the fluid 25 inlet valve will be closed and the fluid outlet valve will be opened.

5. A diving platform, comprising a platform body, a vertically arranged elongated supporting means for the body having vertical rectilinear movement, fluid means for effecting the straight upward movement of the supporting means to a predetermined height, means facilitating the lowering of the supporting means by relief of said fluid means to a predetermined lowered 40 position, means operating upon the application of a weight to the body when the latter is in its lowered position whereby the said fluid means for raising the supporting means and platform will be made effective, and means operating upon movement of the platform to the said predetermined raised position for effecting the stopping of the upward movement of the platform and making operative the said means facilitating the lowering of the platform to the said predetermined lowered position.

6. A diving platform structure, comprising a vertically disposed cylinder, a sleeve vertically reciprocable in the upper part of the cylinder and projecting beyond the top thereof, a tubular rod extending longitudinally through the sleeve, a platform secured at the upper end of the rod, a piston secured to the lower end of the rod and to said sleeve, said rod being open at its lower end into the lower part of the cylinder, a fluid pipe line leading into the lower part of the cylinder, a control valve for said pipe line, a fluid outlet leading from the lower part of the cylinder, a valve controlling said outlet, means coupling said valves for simultaneous movement, 65 one of said valves being open when the other one is closed, a rod within the cylinder having an end extending into said tubular rod, a stop body secured to said last rod beneath said piston and normally in spaced relation therewith, a rock shaft in the lower part of the cylinder connected with said valve coupling means, and a link connection between said rock shaft and said last-mentioned rod, said piston when forced 70 downwardly against said stop actuating said link 75

- mechanism to shift said fluid inlet and outlet valves respectively to open and closed positions, and stop means carried upon said last rod for engagement by the piston when the platform is moved upwardly to a predetermined position for shifting said rock shaft to a position where said fluid inlet and outlet valves will be shifted respectively to closed and opened positions.
7. A diving platform of the character described, comprising a vertically disposed cylinder, a piston in said cylinder, a tubular rod extending upwardly from the piston and opening at its lower end through the piston into the cylinder, a platform upon the upper end of the rod, resilient means maintaining the platform in a predetermined lowered position, a fluid inlet control valve for the lower end of the cylinder, a fluid outlet control valve for the lower end of the cylinder, coupling means for said valves whereby the same will operate simultaneously, one of said valves being opened when the other one is closed, a rock shaft extending transversely through the cylinder below the piston, a linkage mechanism coupling the rock shaft with the valves, an actuating rod longitudinally reciprocable in the cylinder and extending into said tubular rod, coupling means between the lower end of said actuating rod and the rock shaft, stop means upon the actuating rod engaged by the piston upon movement of the platform downwardly against said resilient means to actuate the linkage mechanism to a position where the fluid inlet and exhaust valves will be respectively opened and closed, and means establishing connection between the actuating rod and tubular rod when the piston reaches the upward limit of its movement for actuating the linkage mechanism to a

position where the fluid inlet and exhaust valves will be respectively closed and opened.

8. A device of the character described, comprising a vertical cylinder, a piston in and extending from the upper end of the cylinder, means for conducting fluid under pressure into the cylinder beneath the piston and for conducting fluid out of the cylinder, valves controlling the in-flow and out-flow of fluid through said conducting means, and mechanism operatively coupled with the piston which is so constructed and arranged as to actuate the valves upon application of pressure to the piston when it is down, to establish in-flow of fluid to the cylinder and shut off out-flow and to shut off in-flow and permit out-flow of fluid from the cylinder when the piston reaches a predetermined raised position.

9. A device of the character described, comprising a vertical cylinder, a platform supporting piston reciprocable therein, a valve controlled inlet for conducting fluid under pressure into the cylinder to effect movement of the piston upwardly, a valve controlled outlet for the cylinder, coupling means between the valves by which one valve is closed when the other valve is open, and mechanism operatively coupling the piston with said valve which is so constructed and arranged that when the piston is moved downwardly into the cylinder beyond a predetermined position the valves will be shifted to open the inlet and close the outlet and when the piston is moved upwardly out of the cylinder a predetermined distance, the valves will be reversely shifted to close the inlet and open the outlet.

JAY G. STEPHENSON.
